(57) **CLAIM**

The ornamental design for a portion of a protector for a wrist watch, as shown and described.

DESCRIPTION

FIG. 1 is a front elevational view of a portion of a protector for a wrist watch showing my new design;
FIG. 2 is a right side elevational view thereof;
FIG. 3 is a left side elevational view thereof;
FIG. 4 is a top plan view thereof;
FIG. 5 is a bottom plan view thereof;
FIG. 6 is a rear elevational view thereof;
FIG. 7 is a front, bottom and right side perspective view thereof; and,
FIG. 8 is a reference view showing the state of use of the portion of a protector for a wrist watch; and the broken line showing of the remaining parts of the portion is for illustrative purposes only and forms no part of the claimed design.
The broken line showings of portions of a watch in FIGS. 1-7 are for illustrative purposes only and form no part of the claimed design.
